(57) **CLAIM**

The ornamental design for a motor vehicle and/or toy replica thereof, as shown and described.

DESCRIPTION

FIG. 1 is a front and left side perspective view of a vehicle showing my new design;

FIG. 2 is a rear and left side perspective view thereof;

FIG. 3 is a front and right side perspective view thereof;

FIG. 4 is a rear and right side perspective view thereof;

FIG. 5 is a front view thereof;

FIG. 6 is a rear view thereof;

FIG. 7 is a left side view thereof;

FIG. 8 is a right side view thereof; and,

FIG. 9 is a top plan view thereof.

The bottom view of the motor vehicle is not seen during ordinary use and is not part of the claimed design. The broken lines in FIGS. 1-9 depict environment and the elements depicted in these broken lines form no part of the claimed design.

1 Claim, 9 Drawing Sheets
